THROTTLE CONTROL DEVICE

Edward D. Johnson, St. Louis, Mo., assignor to
 Wagner Electric Corporation, St. Louis, Mo., a
 corporation of Delaware

Application April 23, 1947, Serial No. 743,353

5 Claims. (Cl. 121—38)

1

This invention relates to automatically operated devices for actuating the throttle for an automotive engine during power transmission ratio changes and the object of the invention is to provide a device which will operate the throttle in a proper manner by first quickly partially opening the throttle to increase the engine speed before the clutch is engaged and thereafter slowly continuing the opening movement of the throttle to bring the engine up to a desired speed.

In the drawings Figure 1 is an end view of the throttle operating device; and

Figure 2 shows a longitudinal sectional view of the device taken along the line 2—2 of Figure 1 and connected to a throttle valve and a control valve schematically illustrated.

The throttle actuating pressure fluid device comprises a housing 1 to which a cap 2 is removably secured by a plurality of screws 3. The closure 4 for the cylinder in housing 1 is a diaphragm which is clamped between housing 1 and cap 2. A piston 5 in the cylinder is provided with a sealing cup 6 on its one end secured thereto by means of a washer and a screw 7. A piston rod 8 is secured to the other end of the piston and extends through bore 9 of housing 1. A spring 10 for returning the piston to the illustrated position is interposed between piston 5 and housing 1 and surrounds piston rod 8 with one end of the spring engaging shoulder 11. A nut 12 is threaded onto the exposed end of piston rod 8 for the purpose of adjusting the extent of return movement of piston 5.

A throttle or butterfly valve 13 is pivotally mounted in the intake 14 for the manifold of an engine. Valve 13 is operatively connected to piston rod 8 through linkage 15 and a suitable bell-crank 16. The throttle valve is normally manually controlled and the fluid pressure operated device is operative only during a speed ratio change period and the period immediately subsequent thereto and overrides the action of the manual control during these two periods, as is well known in the art.

The housing 1 and cap 2 are each provided with finished diaphragm motion limiting abutment surfaces 17 and 18 which cooperate with diaphragm reinforcing discs 19 and 20, respectively. A spring 21 disposed in chamber 22 causes diaphragm 4 to normally assume the position shown wherein disc 19 engages surface 17.

Diaphragm assembly 4, 19 and 20 is provided with a cylinder chamber exhaust check valve assembly 23 which is engageable with seat 23b. The valve 23 is maintained in seated position by

spring 23a and has a bleeder passageway 24 which establishes communication between cap chamber 22 and cylinder chamber 25.

Cap 2 is provided with a port 26 to which one end of a conduit 27 is connected that terminates in chamber 28 of valve housing 29 for the inlet and exhaust control valves for the throttle operating device. The valve housing is provided with a valve seat 31 which is engaged by inlet valve 33 mounted on member 34. Exhaust valve 32 is also mounted on member 34 and is engageable with a seat 30 provided on plunger 36. Suitable seals (not shown) may be provided for plunger 36. Plunger spring 35 is arranged between plunger 36 and the valve housing to normally position plunger 36 as illustrated. A spring 37 is provided in chamber 38 to maintain valve 33 in normally closed position. A solenoid 39 constitutes the means for actuating plunger 36. The passageway through plunger 36 constitutes the exhaust port for the throttle actuating device. Port 40 in housing 29 is connected to a suitable source of supply of pressure fluid by means of conduit 41.

Referring now to the operation of the device, a variation of engine and vehicle speed initiates a power transmission ratio shift cycle. Solenoid 39 is connected in a circuit opened and closed by a switch controlled by any suitable means responsive to engine or vehicle speed changes. When energized it moves plunger 36 to the right so that it seats ball valve 32 on seat 30 and thereafter unseats valve 33 from seat 31 permitting pressure fluid to enter cylinder chamber 25 by way of conduit 27, chamber 22 and valve 23. Pressure fluid in chamber 25 forces piston 5 to the left, compressing spring 10 and closing the throttle or butterfly valve 13.

It is essential to the proper operation of the device that the diaphragm 4 undergo a displacement or change in position before the full effect of the pressure fluid entering the cylinder chamber 25 through the check valve 23 can move the piston 5. This displacement is assured by the spring 21. During the period that the throttle is closed, the necessary gear or speed ratio selection is accomplished. The engine or vehicle speed responsive means thereafter causes solenoid 39 to be de-energized, thus enabling spring 35 to restore plunger 36 to the position indicated in Figure 2, thereby providing an outlet or discharge to atmosphere for the pressure fluid in chamber 22, and spring 37 simultaneously seats inlet valve 33 on seat 31.

The sudden opening of the exhaust port 30 releases the fluid in the cap chamber 22 quickly

which just as quickly drops the pressure in the chamber 22. The effect of this pressure drop on the cap side of the diaphragm 4 is to allow the pressure fluid in the cylinder chamber 25 to quickly expand the volume of that chamber. This pressure difference occurs before the inertia of the fluid in chamber 25 can be overcome and flow started in the restricted port 24, thereby producing the desired force in chamber 25 which snaps diaphragm 4 to the right, forcing disc 20 into engagement with surface 18 and compressing spring 21. Chamber 25 is, therefore, enlarged which reduces the pressure of the pressure fluid entrapped in chamber 25.

The reduction in pressure in this chamber releases the stored energy of compressed spring 10 to snap piston 5 rapidly to the right until the spring pressure and the pressure of the entrapped fluid are in balance to quickly partially open the throttle valve. This snap action movement is of sufficient magnitude to actuate an accelerating well associated with the carburetor and closely approximates the initial phase of a proper driver operation. The clutch for the vehicle transmission is now engaged and the spring 10 slowly forces entrapped pressure fluid in enlarged chamber 25 through the bleeder passageway 24 so that the remainder of the return stroke of piston 5 is controlled and imparts a gradual increase in fuel and, therefore, speed to the engine and vehicle which closely approximates the final phase of proper driver operation. Spring 21 returns the diaphragm to the position shown in Figure 2 as the pressure in chamber 25 decreases to a value equal to the pressure in chamber 22.

Having fully described my invention, that which I claim as novel and desire to protect by Letters Patent of the United States is:

1. A control device comprising a cylinder; a piston in said cylinder forming a chamber in one end thereof; a flexible diaphragm engageable with and forming a closure for said cylinder; a cap secured to said cylinder, the interposed flexible diaphragm being engageable with and forming a chamber in the cap; a valve assembly disposed between said chambers for allowing pressure fluid to rapidly pass from said cap chamber to the chamber in said cylinder and having an orifice therein for causing slow return of pressure fluid between the chamber in said cylinder and said cap chamber; a biasing spring for positioning said piston adjacent said diaphragm; a second biasing spring for displacing said diaphragm to a position adjacent the end of said cylinder; a source of pressure fluid; a conduit for placing said source in communication with said cap chamber; and an alternately operable inlet and exhaust valve mechanism disposed in said conduit for controlling the flow of pressure fluid from said source to said cap chamber, and subsequently to said chamber in said cylinder through said valve assembly for moving said piston to compress and store energy in said first mentioned biasing spring, said combined inlet and exhaust valve mechanism being operable under predetermined conditions for releasing the pressure fluid in said second mentioned chamber, thereby allowing said diaphragm to be displaced from adjacent the end of said cylinder against the force of said second biasing spring thus tending to increase the volume of and diminish the pressure in the chamber in said cylinder thereby releasing the energy stored in the compressed spring and allowing rapid movement of said piston toward said dia-

phragm to restore the pressure and volume, and a slow leak-off of pressure fluid from said cylinder chamber through said orifice and said valve mechanism to allow said piston and said diaphragm to slowly assume their original positions.

2. A control device comprising a cylinder; a piston in said cylinder; a diaphragm over one end of said cylinder forming a flexible closure for the cylinder and in connection with said piston forming a chamber in the cylinder; a cap over said diaphragm forming a cap chamber; a spring acting on said piston for holding said piston adjacent said diaphragm; a source of pressure fluid; means for establishing communication between said source and said chamber; a valve in said diaphragm provided with a bleeder passageway; a second valve for applying pressure fluid from said source to the cap chamber side of said diaphragm, said pressure fluid opening said first mentioned valve and entering said cylinder chamber for actuating the piston away from the said one end of said cylinder thereby energizing said piston spring; and an exhaust valve for releasing pressure fluid from said cap chamber, said diaphragm rapidly moving away from said piston so that the pressure fluid in said piston chamber undergoes a pressure decrease rapidly, thereby permitting said piston spring to quickly partially return said piston toward the diaphragm and restore the pressure level in said cylinder chamber, said spring thereafter causing said piston to force the pressure fluid from said cylinder chamber through said bleeder passageway, for causing the piston to slowly continue its movement toward the diaphragm.

3. A valve operating device comprising a cylinder; a piston in said cylinder; a spring for maintaining said piston in one end of said cylinder; a diaphragm secured to said cylinder for closing the end thereof adjacent said piston thereby forming a chamber in one end of said cylinder; a cap over said diaphragm defining a cap chamber therewith, resilient means normally displacing said diaphragm toward said piston; a source of pressure fluid; means for establishing communication between said source and said cap chamber; a valve for admitting pressure fluid from said source into said chamber for moving said piston toward the other end of said cylinder, thereby energizing said spring; check valve means in said diaphragm permitting rapid pressure increases in said cylinder chamber and relatively slow pressure decreases therein for causing said diaphragm to rapidly change its position upon decreases of pressure in said cap chamber, thereby enabling said spring to quickly partially return said piston toward said diaphragm; and exhaust valve means for regulating the exhaust of pressure fluid from said cap chamber for permitting said spring to rapidly and then more slowly complete the return movement of said piston toward said diaphragm.

4. A control device comprising a cylinder; a piston in said cylinder; a biasing spring for maintaining said piston normally in one position; a flexible closure for one end of said cylinder and in cooperation with said piston forming a cylinder chamber in said cylinder; cover means for securing said closure to said cylinder and forming a cover chamber with the closure; a spring for biasing said closure to a position adjacent said piston; a source of pressure fluid; means for establishing communication between said source and said cover chamber; a valve for regulating the supply of pressure fluid to said cover cham-

ber; a second valve in said closure for admitting said pressure fluid to said cylinder chamber for moving said piston toward the other end of said cylinder for energizing said piston biasing spring; and an exhaust valve for releasing pressure fluid from said cover chamber thereby rapidly creating a pressure differential on opposite sides of said closure and causing the pressure fluid in said cylinder chamber to move said closure rapidly away from the piston and compress said spring, thereby permitting said energized piston biasing spring to quickly move said piston partially toward its initial position; said second mentioned valve having an orifice therein for allowing pressure fluid in said cylinder chamber to escape at a fixed rate and said piston biasing spring to slowly complete the movement of said piston to its initial position said closure biasing spring restoring the closure to its initial position adjacent the end of the position upon the fall of pressure in said cylinder chamber.

5. A control device comprising a cylinder, a closure cap for one end of said cylinder, a flexible diaphragm under said cap dividing the space into a cylinder chamber and a cap chamber, spring means normally urging said diaphragm toward said cylinder chamber, a check valve in said diaphragm opening to said cylinder chamber, said check valve having a bleed passage open between said chambers, a spring pressed piston in said

cylinder normally adjacent said diaphragm, a piston rod for said piston extending from said cylinder to transmit a control movement derived from said piston, a source of fluid under pressure, and a fluid flow control valve mechanism connected with said control device and positionable to direct fluid into said cap chamber from said source to fix the position of said diaphragm adjacent said cylinder chamber and to supply fluid through said check valve to said cylinder chamber to drive said piston outwardly in the cylinder relative to said diaphragm and move said piston rod, said control valve mechanism having a fluid exhaust position to initially exhaust said cap chamber and cause a pressure differential across said diaphragm to suddenly displace said diaphragm and simultaneously cause following displacement of said spring pressed piston.
